UNITED STATES PATENT OFFICE.

JENNIE L. BORNSTEIN, OF DAYTON, OHIO.

SANITARY APRON.

1,243,693.

Specification of Letters Patent. Patented Oct. 23, 1917.

Application filed January 22, 1914. Serial No. 813,798.

To all whom it may concern:

Be it known that I, JENNIE L. BORNSTEIN, a citizen of the United States, residing at Dayton, in the county of Montgomery and State of Ohio, have invented new and useful Improvements in Sanitary Aprons, of which the following is a specification.

This invention relates to new and useful improvements in sanitary aprons.

10 The object of my invention is to provide a sanitary apron which is so designed and constructed as to fully protect the person and clothing of the wearer from the menstrual flow, and is particularly serviceable 15 to the above end in cases of bladder trouble where the discharge of fluid is great. In its double form my improved sanitary apron will provide both a front and back protection to the wearer, but it may be used 20 singly with great effectiveness. My improved adjustable belt which is attached to the apron, enables the latter to be fitted to any size waist and worn with ease and comfort.

25 With the above and other incidental objects in view to be hereinafter described in the following specification, I have illustrated one embodiment of my invention in the accompanying drawings, of which Figure 1 is a front elevation of my improved sanitary apron and adjustable belt therefor. Fig. 2 is a side view of the apron in its double form. And Fig. 3 is a section on the line *a—a* of Fig. 1.

35 Throughout the specification and drawings, similar reference characters denote corresponding parts.

In a detailed description of my invention, 1 designates a double fold apron preferably made of moisture proof hospital sheeting. The apron 1 consists of two equal 40 sections 2 and 3 which are preferably integral with each other and adapted to be folded to parallelism upon the line or edge 45 4. Each section is preferably cut in an elliptical shape to afford as great a protection to the wearer as possible. The apron 1 being made of one piece of hospital sheeting, the edge portion 4 is not stitched or 50 perforated in any way to afford moisture a passage therethrough.

The sections 2 and 3 of said apron are united or joined together by tapes 5 and 6, which are stitched or otherwise firmly 55 secured to, and embrace, the lower side edges

of said sections, said tapes extending from the edge 4 to points 7 and 8 located a short distance above it. From the points 7 and 8 to the top of the apron, the sections 2 and 3 thereof are not united, but the side edges 60 of the section 2 are neatly embroidered by tapes 9 and those of the section 3 by tapes 10.

Secured to the apron 1, near the points 7 and 8, are elastic tabs or loops 11 adapted to be attached to the garters or supporters 65 of the wearer to prevent the apron from slipping up.

The belt proper of my improved sanitary apron consists of a band 12 of tape or other like material, provided with a buckle 13 70 or other fastening means to secure the ends of said band firmly together. To one end of the band 12 is stitched or otherwise secured a slide 14, through which, and the buckle 13, the band is adapted to be passed 75 for the purpose of adjusting its length to different sized waists. In other words, as is well known in the art, the slide 14 is adapted to be moved upon the band 12, toward or away from the buckle 13, to lengthen 80 or shorten said band as desired. The buckle 13 and slide 14 are preferably placed at the front for convenience in fastening, adjusting and unfastening the band 12.

Suitably stitched or otherwise secured to 85 the top edges of the apron sections 2 and 3, so as to extend above them, are straps 15 preferably made of tape. If desired, these straps, as well as the band 12, may be made of elastic material to impart resiliency to the 90 belt.

The straps 15 have their upper ends 16 looped to receive the band 12 upon which they are slidably movable. While I preferably attach three straps to an apron section, 95 any number may be employed, but it is important that they be spaced far enough apart to afford as much freedom and coolness to the wearer as possible. Stitched or otherwise secured to the lower middle portions of the straps 15 attached to each apron section, is a reinforcing band 17 made of tape or other suitable material. This band 17 serves to brace and keep in alignment, the straps 15.

100 Stitched or otherwise suitably secured to the two upper corner edges of the apron section 3, are the ends of a supplementary elastic band 18 which extends forwardly a sufficient distance to encircle the waist of the 110

wearer. (See Figs. 2 and 3). This supplementary band 18 forms an additional means of firmly holding the apron to the body.

A downwardly extending yoke 19 is provided at the front of the belt to receive one end of a sanitary pad or napkin, the other end of which may be secured to the back part of said belt. The yoke 19 consists of a piece of tape having downwardly extending portions 20 whose upper ends are looped to receive the band 12. The depending portions 20 preferably straddle the middle strap 15 in order that the yoke 19 may be securely held thereby against lateral movement. By 15 folding the tape diagonally at the lower ends of the depending portions 20, and stitching or otherwise securing the diagonal folds of each end together, a horizontal portion 21 is formed to which one end of a sanitary napkin or pad may be firmly secured.

In operation, the apron 1 is placed in a position between the limbs of the wearer after the feet are first slipped through the supplementary band 18. The apron is then brought 25 up toward the wearer's waist, with the section 2 at the front and the section 3 at the back. The ends of the band 12 are then fastened firmly together by the buckle 13, and said band adjusted, by the slide 14, to 30 comfortably and firmly fit the waist of the wearer. The loops or tabs 11 are then ready to be secured to the garters or supporters for the purpose of preventing the apron from slipping up.

35 As has been observed, my improved apron, when worn, will fully prevent the clothing of the wearer, both at the front and back, from being soiled by the discharged men-

strual fluid. It will also protect from the menstrual flow, the bed clothing or other material with which the body comes in contact, and in cases of illness, will fully absorb all bladder discharges. The adjustable belt enables the apron to be easily put on and adjusted, and worn with ease and comfort.

40 I do not wish to be limited to the details of construction and arrangement herein shown and described, and any changes or modifications may be made therein within the scope of the subjoined claim.

45 Having described my invention, I claim:

A sanitary apron comprising a single elongated piece of moisture proof material bent upon itself about a common straight lower edge, to form two equal sections, the side edges of each section curving outwardly and inwardly, in an even manner, from the common lower edge to an upper straight edge, stitching means for securing the lower side edges of one section to the corresponding lower 50 side edges of the other section, said stitching means passing intermittently through the corresponding side edges of said sections to two respective terminal points an equal distance below the middle portion of the garment to provide two free flap portions, and means extending upwardly from the outside of said flap portions to secure the latter to the body of the wearer, substantially as described.

55 In testimony whereof I have hereunto set my hand this 21st day of January, 1914.

70 JENNIE L. BORNSTEIN.
